[57] CLAIM

The ornamental design for a combined desk, storage and enclosure, as shown and described.

DESCRIPTION

FIG. 1 is a top left front perspective view of a first embodiment of a combined desk, storage and enclosure in accordance with this invention shown in an open configuration; FIG. 2 is a front elevation thereof in the closed configuration;

FIG. 3 is a right side elevation thereof;

FIG. 4 is a left side elevation thereof;

FIG. 5 is a top plan view thereof;

FIG. 6 is a bottom plan view thereof;

FIG. 7 is a rear elevation thereof;

FIG. 8 is a front elevation of an alternative embodiment of the design in a closed configuration;

FIG. 9 is a right side elevation thereof;

FIG. 10 is a left side elevation thereof;

FIG. 11 is a rear elevation thereof;

FIG. 12 is a top plan view thereof; and,

FIG. 13 is a bottom plan view thereof.
